INVENTOR:

Gordon M. Evans,

BY

John P. Barber

ATTORNEY.

UNITED STATES PATENT OFFICE

GORDON M. EVANS, OF NEW YORK, N. Y., ASSIGNOR TO BUDD WHEEL COMPANY, OF PHILADELPHIA, PENNSYLVANIA, A CORPORATION OF PENNSYLVANIA

METHOD OF MAKING BRAKE DRUMS

Application filed February 29, 1928. Serial No. 257,815.

The present invention comprises a method of making brake drums and other similar articles. The primary object of the invention is the provision of a method whereby the braking surfaces of the drum are made perfectly cylindrical, all taper and "out of roundness" being eliminated. The invention is therefore adaptable not only to the manufacture of brake drums, but also to any other use wherein similar results are desired.

Other objects, and the advantages of the invention will become apparent from the subjoined specification and claim. The attached drawings form a part of said specification and comprise:

Figure 1, an inside plan view of a roughly-formed drum, as drawn from the flat blank;

Figs. 2 and 3, successive sectional views of the drum before and during the contracting or "shrinking" operation;

Fig. 4, a similar sectional view of the drum after machining, and

Fig. 5, a fragmentary sectional view of the drum attached to a hub.

When brake drums, or other articles similar to the drum 10 shown in the drawings, are drawn or pressed from flat blanks or sheets of metal (usually steel), the flange 12 of said drum is flared, or coned, as shown in Figures 1 and 2, the said flange 12 extending from the web 11 of the drum at some angle other than a right angle. This is due to the combined effect of the resilience of the metal and the provision of clearance between the punch 35 and lower die of the forming dies. Since both of these factors are inherent in the metal and due to the method of forming, the above condition has been accepted heretofore and remedied by machining off the excess metal 40 to obtain perfectly cylindrical inside and outside surfaces on the flange 12. Because of the machining operation, a thicker blank is needed than the circumstances require, in order to provide the proper thickness of 45 flange in the finished article.

The present invention eliminates the loss of both time and material due to the above usage and produces a more uniform and economical structure. The blank is drawn, or 50 cupped, just as in the prior method, leaving

the flange 12, in the conical or flared shape. Instead of machining this flange to a cylinder, however, the drum is next placed in the dies 13 of a contracting or "shrinking" machine, similar to that shown in the patent to 55 Grotnes, numbered 1,407,148, dated Feb. 21, 1922, in which a circularly-arranged group of such dies are shown having mechanism to move them forcibly inward toward a common center upon a ring, then contracting or 60 "shrinking" the ring to any desired degree. Having placed the drum in the dies of the above machine (herein represented by the dies 13) the said machine is set in motion in the direction of the arrows 14, Figs. 2 and 3. 65 In this way, the flange 12 is reduced to a true cylinder. There remains only the operation of grinding, or lightly machining the working surfaces of the drum (as in Figure 4) to produce a finished product. The last step 70 serves to give an even surface, free from small defects, for the brake shoes to operate upon. The lines 1—1 common to Figures 2, 3 and 4 indicate, in an exaggerated way, the changes made by each operation. 75

The effect of the "shrinking" operation may readily be confined solely to the flange, making it possible to treat malformed drums which (as shown in Figure 5) have already been mounted on a hub 15. By contracting 80 such mounted drums and taking a light machining or grinding cut over the working faces thereof, the original or desired concentricity and cylindrical shape may be restored or obtained. 85

What I claim is:—

The method of making a brake drum or like article, comprising the forming of said drum from a flat plate into a substantially flat web with a circumferential flange extending from said web in the form of a frustoconical shape, and exerting radially inward pressure on said flange and retaining said flange free of interior support during the period of exertion of said inward pressure. 95

In testimony whereof I hereunto affix my signature.

GORDON M. EVANS.
